UNITED STATES PATENT OFFICE.

GEORGE G. SCHROEDER, OF WASHINGTON, DISTRICT OF COLUMBIA.

AERIAL TRANSPORTATION SYSTEM.

No. 841,579.

Specification of Letters Patent.

Patented Jan. 15, 1907.

Application filed May 16, 1904. Renewed June 25, 1906. Serial No. 323,343.

To all whom it may concern:

Be it known that I, GEORGE G. SCHROEDER, a citizen of the United States, residing at Washington, in the District of Columbia, 5 have invented new and useful Improvements in Aerial Transportation Systems, of which the following is a specification.

This invention has relation to aerial transportation systems; and it consists in the novel 10 construction and arrangement of its parts, as hereinafter shown and described.

The object of the invention is to provide a system such as indicated and which is especially adapted to transport parcels, merchandise, mail-matter, light freight, &c., from one station to another along the said 15 system.

In addition to carrying mail and express matter the system may be used to advantage 20 in rough mining districts for the purpose of transporting ores, &c., from inaccessible points in the mountains to the coast or to places having railroad or water facilities and also for carrying supplies and machinery 25 to the mines. This system is especially desirable for such use, for in its erection and operation it is not necessary to grade the earth. Consequently great saving is effected, and in case the mineral deposits should run 30 out the system may be taken down and removed to other places without loss, as would be the case if roads were graded. In such districts the system may be provided with cars or coaches for carrying persons as well 35 as receptacles for carrying freight.

In the transportation of mail and express in rural districts and from one city to another the system is provided with way-stations where the receptacles carrying the 40 matter may be stopped, unloaded, and re-loaded, and forwarded upon its way. In operating the system for this purpose it will be necessary to connect all of the stations by telegraph or other communication in order 45 that the operator at one terminal station when despatching a motor may notify all operators at way-stations at which the motor should stop for the delivery of matter, it being understood that should a way-station 50 have matter to be transported the operator may stop any motor at such station for the purpose of placing the matter in the receptacle.

The stations along the line are provided 55 with devices which remain in such positions normally as to automatically stop all motors

passing the station; but these devices may be so set as not to interfere with or stop the motors. At the terminal stations devices are provided for automatically checking the 60 speed of and stopping the motors. The checking devices at both the terminal and intermediate stations may be operated to release the motors and attachments at any desired time. 65

The system consists, primarily, of towers or poles erected upon the earth at suitable intervals apart. At the top of such towers or poles are strung telegraph or telephone wires, as desired, and upon cross-arms attached to 70 the towers or poles are strung an upper cable adapted to sustain the weight of the motors and contents thereof and serving as a track for the same. Just below said cable is strung a current-conducting wire, which is supported 75 by said cable, but insulated therefrom. The trolley-wheel of the motor passes along this wire in contact therewith. At the stations the current-conducting wire is provided with insulated sections which as soon as the trolley passes thereon cuts off the current from the motor, and consequently the said motor begins to stop and is carried along by the momentum only that it has gained while the current was passing therethrough. At the 80 stations the cable is carried up in elevated sections, over which the motor and its attachments must pass. This further retards the speed of the motor, and when the receptacle engages the automatic braking device 85 90 the motor is readily brought to a state of rest.

At the stations electric connections are provided which connect the adjacent ends of the current-wire and pass around the insulated sections above referred to. Consequently when the motor is again started upon its journey it is supplied with the electric current as soon as it passes over the insulated section of the current-wire. The insulated section of the current wire at the points of 95 junction extends in alinement with the main portion of the current-wire in order to act as an anchor to keep the said current-wire taut and also to act as a track or guide for the trolley-wheel while the motor is at the station 100 or passing through the same.

Where the receptacles carried by the motor are intended for the transmission of both mail and express matter, the said receptacle is divided into two or more compartments, 110 each being provided with a door, to the lock of one of which the mail agent will have

a key, while the express agent will have a key to the compartment containing the express. Thus the mail may be transported in safety, as it can be handled only by the proper persons provided for this purpose.

In the accompanying drawings, Figure 1 is a side elevation of a portion of the system for aerial transportation. Fig. 2 is a transverse sectional view of the system and motor. Fig. 3 is a side elevation of a station, showing one form of construction for transmitting the current past the station. Fig. 4 is a perspective view of a plate used on the towers or poles for supporting the cross-arms. Fig. 5 is a side elevation of a station, showing another form of construction for transmitting the current past the station. Fig. 6 is a side elevation of a pole located at a station and showing the arrangement of the construction for transmitting the current past the same. Fig. 7 is a side elevation of a braking or checking device used at stations. Fig. 8 is a sectional view of one of the members of said braking device. Fig. 9 is an end view of one of the members of the braking device, and Fig. 10 is a sectional view of a terminal buffer.

Throughout the system the poles or towers 1 are erected at suitable intervals apart. At the tops of said poles or towers are located the cross-arms 2, which are adapted to carry the telegraph or telephone wires 3. Below the cross-arms 2 are located the cross-arms 4. When poles are used, as illustrated in the drawings, the said cross-arms 4 are braced to the poles by means of the plates 5. The said plates 5 are similar in construction and are provided with vertical depressions 6 for the reception of the pole 5, and the horizontal depressions 7, adapted to receive the cross-arms 4, the intermediate portions of the said plates between the depressions 6 and 7 serving as braces and being bolted together, as at 8. At the outer ends of the arms 4 4 the cable 9 is strung, and below said cable 45 and extending parallel with the same is located the current-conducting wire 10, the said wire being supported from the cable 9 by means of the supports 11, which are insulated from the cable 9 by the insulation 12. The motor 13 is adapted to travel upon the cable 9. Said motor may be of any desired construction. The motor shown in the drawings consists of the stationary field 14, which receives the armature 15, which is adapted to rotate. The spider 16 is attached to the shaft of the armature 15 and has its ends fixed to the ring 17, which surrounds the field 14 of the motor and is provided with a ball-bearing 18. The outer periphery of the ring 17 is grooved to receive the cable 9. The hanger 19 is attached at its upper end to the casing of the motor-field 14 and extends down past the cable 9 and wire 10 and is attached to the receptacle 20. The said hanger 19 is provided with a trolley-wheel 21,

which engages the under side of the current-conducting wire 10, the overlapping spring-plates 22 22 being attached at their lower ends to the shaft of the trolley-wheel 21 and pass up over the wire 10 in order to prevent the trolley-wheel from jumping from the wire 10. The electrical connection 23 is attached at its upper end to the field 14 of the motor and is provided with the switch 24, which in turn is connected by the wire 25 with the trolley-wheel 21. (See Fig. 2.)

At intervals along the line the system is provided with stations 26. At points approaching each said station the cable 9 is carried up and passes through said station and then descends and assumes its general level, while the current-conducting wire 10 is carried down and around the said station and ceases to extend parallel with the cable 9 at such points only. The said current-conducting wire at the stations is substituted by an insulated section 27, which extends through the station 26 parallel to the cable 9 and is adapted to guide the trolley-wheel of the motor and also acts as a guy or anchor for the ends of the current-conducting wire 10. The section 27 is electrically disconnected from the ends of the current-conducting wire 10 by means of the insulation 28.

In the construction shown in Fig. 3 the section of wire 10' 10' which carries the current around the station 26 is doubled and is connected at its ends to the supports 11 in the manner as shown.

At each station a checking or stopping device for the motor is provided. It will be observed that the receptacle 20 is cylindrical in shape and pointed at its ends. The said checking or stopping device is adapted to receive and operate upon the said receptacle 20. The checking or stopping device consists of a series of brakes, all being similar in construction, but gradually increasing in degree of braking strength.

Each individual brake consists of a number of arms 30, pivotally supported at the point 31. Said arms are arranged parallel to each other and almost describe a circle in cross-section, (see Fig. 9,) the space 32 being provided at the top in order that the hangers 33 of the motor may pass through the brake. The band-spring 33 nearly surrounds one end of the braking device and is adapted to hold the said ends in toward each other, and the tongs 34 surround the opposite ends of the arms 30. The tongs are pivoted together at 35. The shaft 36 passes between the lower ends of the tongs 34, and an eccentric 37 is located on the shaft 36 between the lower ends of each set of tongs. The end of the shaft 36 is provided with the rocker-arm 38, to the end of which is pivoted the pitman 39, which is also attached to the operating-lever 40.

At terminal stations in addition to the

checking or braking devices above described terminal buffers are provided. Said buffer consists of the air-cylinder 41, which is provided in one end with the aperture 42. The piston 43 is located within the cylinder 41 and is normally held against the cylinder-head by the coil-spring 44. The piston-rod 45 passes through the head of the cylinder 41 and is provided at its outer end with the socket 46, which is adapted to receive the pointed end of the receptacle 20.

The operation of the invention is as follows: The motor 13 is started upon its journey and when it arrives at a station 26 15 passes up the inclined portion of the cable 9, and as the trolley which passes over the insulation 28 the current is cut off from the motor; but it continues to travel by reason of the momentum that it has gained while subjected to the current. However, as the motor ascends the inclined portion of the cable 9 to enter the station 26 its speed is somewhat checked. When it enters the station 26, the receptacle 20 passes into the checking 20 and braking devices, which are normally set to engage the sides of the receptacle 20 and offer frictional contact therewith, it being understood that the tension of the first spring 33 is less than that of the other springs 25 and that the tension of the said springs gradually increases. Thus the inner sides of the arms 33 bear against the sides of the receptacle 20, and it is brought to a state of rest. The operator then swings the lever 40, 30 which causes the shaft 36 to describe a partial rotation, and the eccentrics 37, bearing against the lower ends of the tongs 34, force the said lower ends apart and contract the upper ends of the same. This presses the 35 opposite ends of the arms 30 to the ends upon which the springs 33 are located in, and consequently the ends of the said arms under the springs 33 are forced out. Thus the receptacle 20 is released, and it may be moved 40 along the cable 9 until it is cleared of the checking or braking device, where it may be unloaded and reloaded, after which it is run out of the opposite side of the station 26 and down the inclined portion of the cable 9, and 45 as soon as the trolley engages the live position of the wire 10 the motor is electrically supplied and the device passes on to the next station, where the operation above described 50 may be repeated.

Should it not be intended to have the motor stop at a station, the operator may throw the lever 40, so that there will be no frictional contact between the arms 30 and a receptacle 20, in which case the motor will pass 55 on through the station and continue its journey.

At terminal stations the end of the receptacle 20 enters the recess 46, and the piston 45 is moved back and compresses the air in 60 the cylinder 41 and forces the same out

gradually through the outlet 42, it being understood that before the end of the receptacle 20 engages the socket 46 the said receptacle has passed through a series of checking or braking devices. 7c

As indicated in Fig. 1, the said receptacle 20 may be divided into several compartments, each of which is provided with a separate door. Thus mail-matter may be sent in one compartment and express matter in another compartment, the mail agents at the stations having keys to the mail-compartment and the express agents at the stations having keys to the express-compartment. 75

In the event that the receptacle 20 is made 80 of any considerable length the supplemental hangers and wheels 47 may be provided and located at or near the ends of the receptacle in order to help to sustain the weight of the same and its contents and also to prevent 85 any tendency to vertical rocking.

Having described my invention, what I claim as new, and desire to secure by Letters Patent, is—

1. A system of transportation consisting 90 of an elevated track passing way-stations, and braking devices located at the way-stations below said track.

2. An electric system of transportation consisting of an elevated track passing way- 95 stations and having a trolley-wheel guide located below the same, and braking devices located at the way-stations below said track and trolley-wheel guide.

3. An electric system of transportation 100 consisting of an elevated track passing way-stations and having an insulated trolley-wheel guide located below the same, and braking devices located at the way-stations below said track and trolley-wheel guide. 105

4. An electric system of transportation consisting of a track passing way-stations, a current-conductor extending parallel with said track, but passing around the stations out of parallel with the track, and braking 110 devices located at the way-stations.

5. An electric system of transportation consisting of a track passing way-stations and a current-conductor extending parallel with said track, but passing around said stations out of parallel with the track, insulated 115 sections connecting the ends of the current-conductor at the stations and passing through the stations parallel to said track, and braking devices located at the stations. 120

6. A system of transportation consisting of a track passing way-stations and having elevated portions at said stations, and braking devices located below said elevated portions. 125

7. An electric system of transportation consisting of a track passing way-stations and having elevated portions at said stations, and a current-conductor extending parallel with said track, but passing out of parallel 130

with said track at said elevated portions thereof.

8. An electric system of transportation consisting of a track passing way-stations and having elevated portions at said stations, and a current-conductor extending parallel with said track, and insulated sections connecting the ends of said current-conductor at the stations and passing through the stations parallel to said track.

9. An electric system of transportation consisting of a track passing way-stations, and a current-conductor extending parallel with said track, but passing around said stations out of parallel with the track, insulated sections attached to the ends of said current-conductors and serving as an anchor to maintain the same taut and passing through the stations parallel to the track.

10. In a system such as described, a station, a track passing therethrough and adapted to support a car, and braking devices located in the station and adapted to receive and engage the body of the car and offer resistance thereto.

11. In a system such as described, a station, a track passing therethrough and adapted to support a car, a series of braking devices located in the station and adapted to engage the car and offer resistance thereto, the resisting power of said braking devices gradually increasing in intensity.

In testimony whereof I hereunto affix my signature in the presence of two witnesses.

GEORGE G. SCHROEDER.
